UNITED STATES PATENT OFFICE.

STEPHEN A. MISCHANSKI, OF BAYONNE, NEW JERSEY, ASSIGNOR OF ONE-HALF TO
ALEX WOJTKOWSKI, OF BAYONNE, NEW JERSEY.

GAME APPARATUS.

1,276,676.

Specification of Letters Patent. Patented Aug. 20, 1918.

Application filed December 1, 1917. Serial No. 204,846.

To all whom it may concern:

Be it known that I, STEPHEN A. MISCHANSKI, a subject of the Emperor of Austria, but having declared my intention to become a citizen of the United States, and a resident of Bayonne, in the county of Hudson and State of New Jersey, have invented a new and Improved Game Apparatus, of which the following is a full, clear, and exact description.

This invention relates to games and toys and has particular reference to an apparatus involving, more or less, the features of a game of chance and in any of its forms involves the combination of a table or stand having a series of pits or pockets variously graded as to score values, a series of balls or the like, and a projecting device housed in a secluded portion of the apparatus but adapted to eject forcibly the several balls in succession from the hidden or secluded chamber or reservoir so that they shall be brought into the general field of the pits or pockets in the playing of the game.

Among the objects of the invention, therefore, is to provide an apparatus including a rotary member for the actuation of the ejector and so arranged that the projectiles or balls shall be acted on in rapid succession or in accordance with the speed of rotation of the rotary member.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view of one form of my improvement.

Fig. 2 is a vertical longitudinal section of the same on the line 2—2.

Fig. 3 is an elevation looking toward the right hand end of the device as seen in Fig. 1.

Fig. 4 is a vertical transverse section on the line 4—4 of Fig. 2.

Fig. 5 is a sectional detail on the line 5—5 of Fig. 4.

Fig. 6 is a side elevation of what may be termed the magazine or abutment member. 55

Fig. 7 is a diagram of somewhat the character of Fig. 4, but showing in dotted lines the path of the ejector spring with respect to the cam groove formed in the abutment member. 60

Fig. 8 is a plan view of a modified form of the invention.

Fig. 9 is a vertical transverse section of the same on the line 9—9.

Fig. 10 is a vertical section at right angles to Fig. 9 and on the line 10—10 thereof, but indicating the rotary actuator cam in a changed position; and

Fig. 11 is a detail view of the ejector portions of the device corresponding to the central part of Fig. 9, but with the actuator cam in that position in which the cam is at its maximum throw or just prior to the release of the actuator. 70

Referring now more particularly to the form of the invention first referred to I show a table or rack comprising a substantially flat board 15 having a smooth upper surface and of any desired relative proportions or dimensions. This board may be supported in any suitable manner or position but preferably in a level position as upon feet 16 and 17 constituting portions of end pieces 18 and 19, the latter constituting what I term herein as an abutment or magazine member. The board 15 is provided also with upwardly projecting side walls or flanges 20. At any desired place between the end members 18 and 19 is arranged a transverse plate or baffle 21 shown in this instance as arranged in a vertical plane parallel to the end members and at approximately one third of the distance from the member 18 toward the abutment member. The baffle member is provided with a gateway 22 at the center of its lower edge. This baffle divides the board into two fields A and B, the field A being the larger and nearer the abutment member 19. 85 90 95

The abutment member as shown best in Fig. 6 is channeled or slotted at 23, the channel extending from an upper corner diagonally downwardly toward the center thereof where the channel terminates at a level just slightly below the level of the top 105 of the board 15. The upper edge of the

abutment member 19 is inclined rearwardly toward the channel 23 and supports thereon a tubular receiver 24 which for convenience may be made as an integral part of a face plate 25 secured to the outer end or face of the abutment member 19, and which is substantially flat but for the tubular receiver. The receiver tube extends to and communicates with the upper end of the channel 23 and these parts taken together constitute a magazine for any suitable number of projectiles indicated in the form of balls 26, such as marbles, to be used in the playing of the game. The upper front end of the tubular receiver 24 is open whereby the balls may be inserted into the magazine where they roll in single file to the pit at 27 where the lowermost one will rest upon a plate and against a stop lug or the like 28 which holds such ball in the vertical center of the abutment member and in direct line with the center of the gateway 22 in the distant baffle board. This lowermost ball in the pit lies just at the innermost end of a hood 29 constituting a guard or screen and having an open end directed toward the baffle board. This guard or screen serves several purposes among which are to add interest to the game when played by small children in insuring that the balls shall be projected from a practically hidden source, and it also serves to prevent tampering with the balls or changing their position with respect to the projecting apparatus.

35 In this form of the invention the actuating or projecting devices include a disk-like rotary member 30 pivoted for rotation around its center and provided with a handle or crank 31 the inner end of which projects through the disk at 32 and through the face plate 25 constituting the pivot around which the disk rotates and having a head on its inner end serving to hold the disk in fixed position upon the face plate.

40 At the bottom of the disk is arranged a stationary guide 33 which serves to hold the lower edge of the disk from displacement laterally from the face plate.

45 The face plate 25 is provided with an arc-shaped slot 34, the outer edge of which is substantially concentric with the pivot 32 while the inner edge thereof is eccentric as indicated at 35. The slot 34 lies over a cam groove or depression 36 formed in the abutment member 19. The lower end of the groove 36 is enlarged and opens into the pit 27. The upper end, however, of the groove is tapered and is cam shaped at 37 substantially the same as the face plate slot which 50 lies thereover. The disk 30 is provided with a slot 38 that is arranged diagonal to a radius of the disk intersecting it or tangential to a circle concentric with the disk but of about one third the diameter of the disk.

55 As an actuator or projecting means for the

balls I provide a leaf spring 39 having one end fixed at 40 to the outer face of the disk just ahead of the slot 38. The free end of the spring is bent inwardly through the slot and terminates directly opposite the lowermost ball at the pit. The space provided between the lug 28 and the lower larger end of the slot 34 is ample for the spring 39 to snap freely therethrough against the lowermost ball whereby this ball is ejected forcibly from the pit through the hood 29 and toward or against the baffle board 21. The free end of the spring at this time passes the lug 28 and is carried with the continued rotation of the disk upwardly along the slot 34 and between the bottom of the cam groove 36 and said lug. The lug, however, acts as already stated to receive and hold the next ball in turn in position to be struck by the spring at the completion of the next rotation of the disk. The free end of the spring during the rotation of the disk is dragged or wiped up over the cam edge 35 of the face plate as indicated in successive dotted line positions in Fig. 7, and finally snaps over the portion 25' of the face plate which is parallel to the slots 38 at the time of delivery of the ball. It will thus be seen that the ejector spring serves to snap forcibly a single ball from the magazine or pit, leaving the remaining balls to roll into position in succession for delivery in turn. The spring 39 being arranged in a diagonal manner or tangential to the small circle described will drag or glide with comparatively little friction or resistance over the outer face of the face plate and still is so arranged that the free end of the spring will pass the lug 28 and not disturb the position of the next ball in turn. The operation of this form of the invention may be briefly summarized as follows: The player will turn the crank and disk in a clockwise direction as indicated by the arrow on Fig. 7 at any desired rate of speed or regularity. At each complete rotation of the disk the spring will snap through the slot 34 and eject the lowermost ball or any ball at the bottom of the pit, driving it suddenly through the hood and causing it usually to impinge against the baffle board 21, whence the ball will roll around the field A with the possibility of locating in some one of a number of recesses indicated at 41 which may be variously identified according to the scoring of the game. In some cases, however, the balls may pass through the gateway 22 and so enter the second field B which may be given a higher value in the final score and so adds greatly to the interest of the game. It sometimes further occurs that the ball will be driven through the gateway 22 and thence returned back through it to field A giving further interest and amusement. This device is simple of construction, easy to

operate and not likely to get out of order or constitute in any way a dangerous plaything. Small children are amused almost indefinitely in the playing of it and the keeping 5 of the score constitutes an educational quality.

In practice the invention may assume a form such as indicated in Figs. 8 to 11 inclusive although the broad principles of the 10 operation are similar to those already set forth. In this form of the invention I provide a table 42 supported as by feet 43 so as to lie preferably level and provided with a bounding upstanding wall or flange 44. 15 This table may be of any suitable size or dimensions. At any convenient point the table is provided with a vertical hole 45 therethrough. Beneath this hole is arranged a pit 46 having a slot or opening 46' in its 20 bottom arranged substantially in the vertical axis of the hole 45. This pit structure may be formed of any suitable material preferably sheet metal so as to provide ample strength and rigidity as well as cheapness 25 for the purpose. At one side the pit structure is provided with a flange or extension 47 constituting a bearing for one end of a rotary tubular magazine 48. This magazine is supported in an inclined position, the outer 30 end thereof being journaled in a bearing 49 adjacent to one side wall or edge of the table. See Fig. 9. The magazine 48 is inclined so that any desired number of balls inserted into the open outer end thereof will 35 roll freely in succession toward the pit and come to rest in the slot or depression 46' thereof. The magazine 48 is provided at its outer end with a crank 50 whereby it is adapted to be turned by the hand of the 40 player in a clock-wise direction as shown by the arrow in Fig. 10.

In this form of the invention the leaf spring 51 is combined with the stop lug feature 52. The spring instead of being 45 connected to the rotating part is fixed at one end at 53 to a stationary portion 54 of the structure, while the free end portion of the spring carries the lug 52. The normal 50 position of the lug is indicated in Fig. 9 where it projects upward through the slot 46' in position to constitute a barrier or stop for the series of balls 26 in the magazine.

A flat spiral cam 55 is secured around the lower end of the magazine 48 and is rotated 55 by the magazine in a plane perpendicular to the axis of the magazine. The plane in which the cam is located intersects the portion of the lug 52 preferably just over the free end of the spring. See Figs. 9 and 11. 60 While the cam is thus rotated the radial throw of the cam acts to force the spring downwardly putting it under tension, carrying the stop lug 52 below the slot 46' permitting the lowermost ball to roll into the slot. 65 See Fig. 11. The moment, however, that the

end of the larger portion of the cam is reached the spring snaps forcibly toward the axis of the magazine with the result that the lug 52 impinges forcibly against the ball located at that time in the slot 46' projecting 70 the ball up through the hole 45 in the table. In this as well as the other form of the invention there is a pronounced click incident to the projecting action and this adds interest also to the playing of the game. 75

56 indicates a baffle supported in any suitable manner as by means of a pedestal 57 directly above the hole 45. This baffle may be of any suitable form depending upon the size or form of the table. As indicated, 80 however, I form it somewhat like a cone with the apex thereof lying in the axis of the hole but spaced above it. The face of the cone, however, is concaved so as to deflect the balls downwardly as well as outwardly when the balls are caused to strike against the same due to the impact of the lug 52. From the baffle 56 the balls drop at some uncertain point upon the table top 85 where they are free to roll with the possibility of landing in any one of a series of pits indicated at 58 which may be variously identified numerically for the purposes of the score. As indicated in Fig. 8 I also mark on the face of the table what would 90 appear to be runways or paths 59 leading from the central hole 45 to the several pits 58. These pits likewise may be given numerical values whereby if any of the balls come to rest thereon the score will be modified 95 accordingly. In any form of the invention the table top may be faced with baize, 100 felt, or the like, indicated at 60.

I claim:

1. The herein described game apparatus 105 comprising, in combination, a table having a series of pockets formed therein, a baffle co-operating with the table top, a pit structure adjacent to the table and having a passageway leading therefrom toward the baffle, 110 one or more projectiles, and rotary means co-operating with the projectiles to eject them singly from the pit toward or against the baffle, whence they may roll into any of 115 said pockets.

2. In a game apparatus of the character set forth, the combination of a board, a baffle arranged over the board, a pit structure co-operating with a portion of the board, there being provided a passageway from the pit 120 toward the baffle, a series of projectiles, and projecting means including a spring and a rotating member to cause the projectiles to be snapped forcibly in succession from the pit toward the baffle. 125

3. In a game apparatus, the combination of a receiving field or board having a series of pockets formed therein, a baffle co-operating with the field, a pit structure adjacent to the field and having a passageway leading 130

toward the baffle, a projectile, means to guide the projectile to the pit, a spring ejector serving to eject the projectile from the pit toward the baffle whence it can be rolled into one of the pockets, and rotary means serving to control the operation of the spring.

4. In a game apparatus, the combination

of a field having variously numbered stations thereon, one or more projectiles, and actuating means coöperating in succession with the projectiles to deliver them upon the field, said actuating means including a spring and cam mechanism acting to control the active position of the spring.

STEPHEN A. MISCHANSKI.

Copies of this patent may be obtained for five cents each, by addressing the "Commissioner of Patents, Washington, D. C."
